CLAIM

The ornamental design for a curb guard, as shown and described.

DESCRIPTION

FIG. 1 is a top perspective view showing a curb guard according to the new design; and

FIG. 2 is a front view thereof.

FIG. 3 is a rear view thereof.

FIG. 4 is a left view thereof.

FIG. 5 is a right view thereof.

FIG. 6 is a top view thereof.

FIG. 7 is a bottom view thereof; and,

FIG. 8 is a bottom perspective view thereof.

The broken lines shown are environmental only and form no part of the claimed design.

1 Claim, 6 Drawing Sheets
